BOGENWERK GESELLSCHAFT MIT BESCHRANKTER HAFTUNG, OF HAMBURG, GER-
MANY

APPARATUS FOR STRAIGHTENING OUT THE ENDS OF BENT PIPES

Application filed June 17, 1930, Serial No. 461,789, and in Germany March 3, 1930.

In producing wrought iron bent pipes, such as elbows, bends or the like, the ends are generally not straight but curved in continuation of the curvature of the bend itself. It has been proposed to straighten out the ends of such bends by the aid of a two-part mold, the two parts or dies, when closing upon one another, encompass a hollow space corresponding to the shape of the bend to be produced. One of such parts is stationary and the other being movable in a direction parallel to the central plane of the bend, two mandrels being arranged to be forced into the ends of the bent pipe, when the movable part of the mold approaches the fixed part. When thus operated upon the ends of the bend are straightened out. However, there is the drawback that the thickness of the wall of the end becomes uneven, because on the inner portion of the end of the bend the material is upset and is thickened, while at the outer portion the material is stretched and thus the wall is thinned and thus weakened. This irregularity in the thickness of the wall of the pipe ends is inconvenient and even disadvantageous. Besides the limited strength against inside pressure the uneven thickness of the wall makes it difficult to attach flanges or to expand the elbow ends to form faucets or sockets or to apply borderings.

The object of the present invention is to straighten out the ends of bent pipes while maintaining uniform thickness of the wall, and if for any reason an unevenness of the thickness of the wall exists to remove such unevenness.

The invention resides in this that a straightening out is effected in such manner that to the same extent in which that portion of the wall which is on the inside of the curvature center is progressively pressed towards the center of the opening or mouth of the bend by a mold section or jaw approaching from outside while at the same time that portion of the wall which is on the outside of the curvature center is pressed correspondingly progressively towards the outside by a mandrel operating within the pipe against the outer part of the opening. Since at every

moment during such straightening operation the inner and the outer halves of the pipe end are pressed uniformly and simultaneously in the same direction the resistance is removed which in the known method causes an upsetting of the inner and stretching of the outer half of the pipe end. 55

Moreover it will be seen that the surplus material on the curvature inside is used up for supplementing that part of the material wanting on the outer curvature side, and this is done by an urging of the material beyond those lateral parts intermediate the inside and outside of the curvature. 60

In case the elbows or bends, the ends of which are to be straightened out, are not uniform with regard to the thickness of the wall an equalization of the thickness of the wall is effected by this method, an urging of the material taking place towards the weaker parts. If elbows and bends are to be operated upon, in which the ends have not the proper dimensions, or are not perfectly circular, or have a slightly too large cross-section the method will have the result of a 75 calibration of the pipe ends. 70

An apparatus for carrying out the method mentioned above may consist of a mandrel and jaws or halves of a mold, which mandrel is given a pivotal movement on the movable jaw closing down. The pivotal movement of the mandrel is carried out in such manner that it presses the outer half of the pipe end outwardly, which is done at the same time when the inner half of the pipe end is pressed in the same direction by the movable jaw. On completing this operation the axis of the mandrel will be in a position tangentially to the central curvature line, corresponding to the central line of the straightened end of the bend. The end is thus straightened out. 85 90

By way of example in the drawings so much of an apparatus is shown diagrammatically as is necessary to illustrate the invention. 95

Fig. 1 is a vertical section of part of the apparatus in a position in which the movable jaw is in upper positon, thus the mold being open. 100

Fig. 2 is an elevation of the same parts of the apparatus in closed position.

Fig. 3 is a section drawn to the line 3—3 of Fig. 1, and

Fig. 4 a section drawn to the line 4—4 of Fig. 2.

Fig. 5 is an end view of the apparatus in the position shown in Fig. 2, and the

Figs. 6 and 7 illustrate an apparatus adapted to be used for bends having a not true circular cross-section or a wall of uneven thickness.

As shown in the drawings the mandrel *a* is formed by a short cylinder provided with a shaft or handle *b* at its end. The diameter of the cylindrical mandrel *a* corresponds to the inner diameter of the bend or pipe end *c*, so that it can be introduced into such end. The bend *c*, the end of which is to be straightened out, is placed into the open mold, that is to say between the fixed jaw *d* and the movable jaw *e* in such manner, that its end abuts against the shoulder *f* on the jaw *e*. The mandrel *a* is subsequently or previously introduced into the bend so as to contact with its front edge against the outer part of the wall at the place inside the bend where the straightened part after being operated upon is to commence. Moreover the mandrel also contacts with its cylindrical part with the edge of the wall of the outer side curvature and moreover on the opposite side also with the inner side curvature of the bend.

When the jaw *e* is moved towards the fixed jaw *d* the mandrel is oscillated about a point where its front edge contacts inside the tube with the outer part of the curvature as a pivot, which pivot point is designated by *x*, Fig. 1. The pivotal movement of the mandrel is effected in the construction shown whereby the lateral shoulder *f* of the jaw *e* contacts with that part of the mandrel *a* projecting out from the end of the bent pipe, and thus by corresponding movement of the jaw *e* a pivotal movement of the mandrel is effected about the pivot *x*. Hereto the jaw *e* tends to press the wall designated by *y* of the inner curved part of the tube end downwards towards the mandrel *a*, the latter at the same time pressing outwardly that part of the outer curved wall of the pipe which is designated by *z*. This operation is carried on progressively until the jaws *e* and *d* are closed upon one another, and the axis of the mandrel *a* forms the continuation of the central line of curvature tangentially, as may be well understood from Fig. 2.

On the jaws *e* and *d* closing upon the mandrel *a* the thickness of the wall is equalized whereby the material on the inner-side of the curvature upon the straightening out will be gradually urged further on towards the outer side of the curvature. Even if the end of the bent pipe is not properly dimensioned or not round in cross section or has an un-

equal thickness of the wall, the pipe end will be given the proper section as will be understood from Figs. 6 and 7, the wall being equalized throughout.

The mandrel *a* of course might be moved or pivoted independently from the movement of the jaw *e* by any desired means.

I claim:—

1. An apparatus for straightening the ends of bent pipes, elbows, bends, or the like, comprising two concave jaws, one being fixed and the other movable towards the fixed jaw, a pivotally movable mandrel having a cylindrical part of a cross-section corresponding to the inner cross-section of the pipe and when inserted into the end of the bent pipe contacting with its outer edge the outer part of the bent pipe, where the straight end is to commence and with its cylindrical part on one side the edge of the outer side curvature, and on the opposite side the inner side curvature of the bend, the first mentioned place of contact forming the pivot point about which the mandrel is pivoted.

2. An apparatus for straightening the ends of bent pipes, elbows, bends or the like, comprising two concave jaws, one being fixed and the other movable towards the fixed jaw, a pivotally movable mandrel having a cylindrical part of a cross-section corresponding to the inner cross-section of the pipe and when inserted into the end of the bent pipe contacting with its outer edge the outer part of the bent pipe, where the straight end is to commence, and with its cylindrical part on one side the edge of the outer side curvature and on the opposite side the inner side curvature of the bend, the first mentioned place of contact forming the pivot point about which the mandrel is moved, the mandrel also contacting the movable jaw to be operated thereby when this jaw moves towards the other jaw.

3. An apparatus for straightening the ends of bent pipes, elbows, bends or the like, comprising a fixed jaw, a movable jaw and a mandrel, adapted to be inserted into the end of the bent pipe and to be pivoted after being inserted by the movable jaw engaging the bent pipe at its end from outside and simultaneously also engaging the mandrel which itself engages the bent pipe from inside, thus straightening out the end of the bent pipe.

4. An apparatus according to claim 1, the movable jaw being provided with an inner shoulder, against which the bent pipe bears with its edge on the curvature inner side when being operated on.

In testimony whereof I have signed my name to this specification.

RUDOLF HIERONYMUS BÖHLING.
